William Reiff William

UNITED STATES PATENT OFFICE.

GURNEY L. SHORT, OF ANGUS, MINNESOTA.

COW-TAIL TIE.

Application filed June 9, 1926. Serial No. 114,871.

This invention relates to a holding device and particularly to a holding device comprising a cow tail tie. As is well known to persons milking cows, the cow often 5 switches her tail about in an effort to disperse flies, and strikes the person milking, in the face. This is exceedingly uncomfortable and often very painful.

It is an object of this invention, therefore, 10 to provide a simple and efficient holder or tie by means of which the cow is prevented from switching her tail.

It is a further object of the invention to provide a cow tail tie or holder comprising 15 a pair of loops or coils of resilient material disposed in substantially the same plane and adapted to grasp the leg or hock of the cow therebetween.

It is more specifically an object of the invention 20 to provide a cow tail tie or holder having spaced loops or coils disposed substantially in one plane and made of resilient wire or similar material from which coils wires extend toward each other and then extend 25 in parallel relation, said parallel portions being rigidly connected by a flat plate, said wires being formed into a spring at one end of said plate and into the bill of a hook co-operating with said plate.

30 These and other objects and advantages of the invention will be fully set forth in the following description made in connection with the accompanying drawings, in which like reference characters refer to similar parts throughout the several views and in which:—

Fig. 1 is a perspective view of the device, showing the rear portion of a cow with the device in operative position thereon;

40 Fig. 2 is a plan view of the device; and

Fig. 3 is a section taken on line 3—3 of Fig. 1, as indicated by the arrows.

Referring to the drawings, a cow tail tie or holder is shown made largely of resilient 45 material, and while various materials might be used, in the embodiment of the invention illustrated the device is shown as made from resilient or spring wire. This wire is formed at one end of the device into loops or coils 5. While these coils may be of various shapes, they are illustrated as substantially circular and each coil is shown as comprising a plurality of convolutions 5^a. It will be noted that the ends of the wire 55 are disposed in the coils 5 and while two or more pieces of wire might be used, pref-

erably and in the embodiment of the invention illustrated, the device is shown as formed from one continuous piece of wire. Each of the coils 5 has a strand 6 of the wire 60 extending from the outer side thereof and tangent thereto, which strands extend towards each other in curved relation and then are extended in straight parallel portions 7. A plate 8 preferably of sheet metal 65 is provided and the edges of this plate are rolled into the sleeves 7^a embracing and rigidly spacing the parallel portions 7 of the wire. At the end of the plate 8 opposite the coils 5, the wire is formed into the 70 coil springs 9 which are of comparatively small diameter having their common axis substantially parallel to the adjacent end of the plate 8. The wire continues from the adjacent ends of the springs 9 and is formed 75 into a loop 10. The loop 10 is held against one side of the plate 8 by the tension of the springs 9 and at its terminal end is bent slightly away from the plate. The loop 10 thus forms the bill of a hook, the shank of 80 which is formed by the plate 8.

In operation the device will be placed on the cow's leg as shown in Fig. 1. The device will simply be pushed onto the said leg, so that the leg is clamped between the adjacent 85 sides of the loops 5. These loops are resiliently held in engagement with the leg by the strands 6. When the device is so in place, the tail of the cow is placed in the hook formed by the plates 8 and 10 and between said members. If desired, of course, the tail may be first engaged in said hook and the device then be placed on the cow's leg. It is apparent that other portions of the cow's leg than that shown can be 90 clamped between the loops 5. When the device is in position as shown in Fig. 1, the tail of the cow is held substantially in stationary position and it is impossible for her to switch her tail into the face of the milker. 100 The device grips the cow's leg with sufficient firmness to hold the tail and at the same time causes no discomfort to the cow.

From the above description it is seen that applicant has provided a very simple and 105 efficient device for the purpose intended. The device comprises only two parts and these are very easily made and assembled. The device is quite small and light and the milker can easily carry the same in his 110 pocket.

It will, of course, be understood that

various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

- 10 1. A cow tail tie comprising a single resilient wire or rod having its ends formed into loops respectively opposed at their sides and adapted to embrace a cow's leg between said sides, said wire having substantially parallel portions extending at one side of said loops, means rigidly secured to and spacing said portions, said wire beyond said portions being bent to form springs and having a loop portion extending from said spring and co-operating with said means to form a hook for clasping the tail of the cow.
- 15 2. A cow tail tie comprising a flexible integral spring member coiled at its ends into loops disposed side by side substantially in the same plane and adapted resiliently to engage a cow's leg between adjacent sides thereof, said member having spaced longitudinally extending portions adjacent said loops, a plate engaging and rigidly spacing said portions, said portions beyond said plate being formed into a spring and into a loop held by said spring against said plate,

said loop and plate constituting a hook for clasping the tail of the cow.

3. A cow tail tie comprising a pair of closed coils disposed substantially in the same plane, resilient arms extending from said coils and having parallel portions, a plate to which said portions are secured in slightly spaced relation, a spring at one end of said plate and a member forming the bill of the hook held against said plate by said spring, said plate forming the shank of said hook.

4. A cow tail holder comprising an integral piece of resilient wire coiled at its ends into multiple strand loops disposed in slightly spaced relation and in substantially the same plane, said wire having strands extending from the remote sides of said loops toward each other, said strands having parallel portions extending away from said loops, a flat plate having its edges formed as sleeves, rigidly embracing said parallel portions and spacing the same, said strands at the end of said plate opposite said loops being coiled into springs and having a loop portion held by said springs extending along and in contact with said plate and forming the bill of the hook of which said plate forms the shank.

In testimony whereof I affix my signature.

GURNEY L. SHORT.
